UNITED STATES PATENT OFFICE.

ADOLPH GREENSPAN, OF BOWLING GREEN, KENTUCKY.

CLOAK OR SKIRT RACK.

SPECIFICATION forming part of Letters Patent No. 643,959, dated February 20, 1900.

Application filed December 4, 1899. Serial No. 739,154. (No model.)

To all whom it may concern:

Be it known that I, ADOLPH GREENSPAN, of 5
Bowling Green, in the county of Warren and
State of Kentucky, have invented a new and
useful Improvement in Cloak or Skirt Racks,
of which the following is a specification.

My invention relates to improvements in
racks for the display of coats, cloaks, and
skirts, and has for its object a rotary rack
10 which is extensible laterally whereby to ac-
commodate cloaks, capes, or coats of all ordi-
nary sizes and which may be so arranged that
it can also be used to display skirts or full-
length cloaks.

15 The invention consists in certain details of
construction and arrangement of the parts,
which will be hereinafter specifically de-
scribed and claimed.

Reference is to be had to the accompanying
20 drawings, forming part of this specification,
in which like characters of reference indicate
corresponding parts in all the views.

Figure 1 is a perspective view of my im-
proved display-rack. Fig. 2 is a vertical de-
25 tail section illustrating the manner of mount-
ing the rotary frame. Fig. 3 is a detail view
illustrating a fluted locking-disk, and Fig. 4
is a detail view illustrating one of the guards.

The standard 10 of my improved rack is of
30 substantially inverted-U shape, as shown, and
is mounted on wheel-supported legs 11, so
that the rack may be conveniently moved
from place to place as required. Stub shafts
or spindles 12 are mounted in the side bars
35 of the said standard, and on each spindle is
secured a wheel 13, consisting of a cruciform
hub 13^a, in each member of which is secured
a tubular spoke 14. The spokes of each hub,
as illustrated, are four in number, and each
40 spoke is normally connected with an opposite
spoke at the other side of the rack by rods 15,
having angularly-bent ends 15^a inserted in
the spokes and held therein by set-screws 16
or other suitable clamping devices.

45 The rods 15 are adapted for the attachment
thereto of the coats, capes, or the like to be
displayed, and it is evident that when it is
desired to display very short articles, such as
infants' sacks, the rods may be held as far as
50 possible in the spokes, and each rod may be
utilized. However, if longer articles are to
be displayed the rods are drawn an adequate

distance out of the spokes and clamped in ad-
justed position.

In order to prevent the articles from becom- 55
ing soiled by contact with the material of
which the rack is made, I pivotally attach
guards 17 to the rods, as shown, by clips 17^a,
fitted in grooves 17^b in the rods, near the an-
gular ends of the latter, the said guards swing- 60
ing with the articles as the rotary frame is
turned.

In order to automatically lock the rotary
display-frame when a rod comes in alinement
with the cross-bar of the standard, I extend 65
the spindles 12 on each side of the standard
10 and form such extensions 12^a approxi-
mately square in cross-section, with threads
12^b on two opposite sides, as shown in Fig. 2.
On the extensions 12^a are inserted fluted 70
locking-disks 18, having square apertures
through which the extensions are received,
so that the disks are forced to turn with the
spindles. A coil-spring 19 presses each disk
against the side of the standard 10 and ten- 75
sion-nuts 20 screw on the extension of the
spindles and bear against the outer ends of
the springs 19.

It is to be understood that the spindles 12
turn with the rotary display-frame. Now 80
when the latter is turned the spring-pressed
disks 18 will also be forced outward and
turned, and as soon as a rod comes in aline-
ment with the cross-bar of the standard the
disks will spring inward and lock the rotary 85
frame, as shown in Fig. 1.

If it is desired to use the rack for the dis-
play of very long garments, such as skirts or
full-length cloaks, one of the rods 15 is en-
tirely withdrawn from its spokes, so as to pro- 90
vide additional space for the articles hang-
ing on an opposite rod.

21 designates a stay-rod connecting the
lower ends of the standard 10, and, if desired,
a spring-curtain 22 may be mounted on such 95
rod, so as to cover the articles when the rack
is not in use.

Having thus described my invention, what
I claim as new, and desire to secure by Letters
Patent, is—

1. A rack for the purpose described, com-
prising a standard having opposing spindles
mounted therein, a rotary frame secured on
said spindles, and disks fitted on said spin-

dles and turning with the latter, said disks being spring-pressed into engagement with the standard whereby to lock the frame, as set forth.

- 5 2. A rack for the purpose described, comprising a standard having opposing stub-spindles mounted therein, a rotary frame secured on said spindles, and spring-pressed fluted disks on said spindles, said disks frictionally engaging said standard, as set forth.
3. A rack for the purpose described, comprising a standard having opposing spindles mounted therein, said spindles being formed with threaded extensions, a frame secured to
- 15 15 said spindles, fluted disks having apertures whereby they are received on the extensions

of the spindles, and being held from turning on said spindles, springs pressing said disks into frictional engagement with the standard, and tension-nuts on the said extensions 20 whereby to compress the springs, as set forth.

4. In a rack for the purpose described, a frame mounted to rotate about a horizontal axis, and guards pivotally connected to said frame at the ends thereof, as set forth. 25

In testimony whereof I have signed my name to this specification in the presence of two subscribing witnesses.

ADOLPH GREENSPAN.
